BALTHASAR ZOPFI, OF SANTA ROSA, CALIFORNIA.

LIFE-SAVING DEVICE.

1,139,624.

Specification of Letters Patent. Patented May 18, 1915.

Application filed December 1, 1913. Serial No. 803,952.

To all whom it may concern:

Be it known that I, BALTHASAR ZOPFI, a citizen of the United States, residing at Santa Rosa, in the county of Sonoma and 5 State of California, have invented new and useful Improvements in Life-Saving Devices, of which the following is a specification.

Although life belts are carried on board 10 ships experience has shown that, for various reasons, there is still much unnecessary loss of life in cases of shipwrecks. Sometimes not enough belts are carried for all the passengers; or, in the shock and confusion 15 of a shipwreck, a passenger will not know where to find the life belt, or the life belts have all been secured by the other passengers; again, it has frequently happened that, from false economy, life belts provided for 20 ships have been made of a cheap material and are insufficiently buoyant to support the passenger. Moreover the ordinary life belt occupies considerable space, which, on board ship, is limited.

25 It is the object of the present invention to provide a life saving device which will be extremely buoyant, occupy almost no space, will be the property of the individual passenger, and will be situated so as to be 30 readily accessible to him.

In the accompanying drawing, Figure 1 35 is a plan view of my improved life saving device, deflated; Fig. 2 is a transverse section thereof, deflated; and Fig. 3 is a transverse section thereof, inflated.

Referring to the drawing, 1 indicates a traveling bag of the character known as a suit case, of any suitable material ordinarily used for this purpose, and comprising a 40 body and a cover hinged thereto in the usual manner. It has preferably two handles 2 as my device is of sufficient buoyancy to support two persons in the water.

45 3 indicates a rectangular rubber bag of length nearly equal to the interior length of the suit case, and to the bag near the middle, preferably at an edge thereof, is secured a metallic externally threaded tube 4. This tube extends through an opening in the lock 50 plate 5 of the suit case, and I preferably make this opening in the form of a slot 7 opening at the edge of the body of the suit case, and almost closed by the side of the cover of the suit case when the suit case is

locked. On said tube is a nut 8 screwed 55 thereon which locks the tube in the slot 7. In the end of the tube is the casing of a pneumatic tire valve. In the suit case is secured by straps 10 either a bicycle pump 11 or a cylinder 12 of compressed air or 60 both. When the bag is deflated it is covered by a strip 13 of canvas, which is used to protect the rubber bag from puncture by sharp articles carried in the bag or by abrasion against ordinary articles therein. 65

The bag is preferably used for carrying articles which the traveler is likely to need on his voyage. When the traveler reaches his berth on the ship, he removes these articles and inflates the bag with the bicycle 70 pump or compressed air cylinder until the bag substantially fills the suit case. In case of a shipwreck, the traveler immediately runs to his berth and seizes the suitcase. It is preferable to secure a strap 14 around the 75 suit case, which strap may be passed through the handles 2 and strapped around the body of the passenger, thus preventing accidental separation of the suit case from the passenger. It has been found by actual trial that 80 a suit case of somewhat small dimensions equipped with my invention possesses sufficient buoyancy to support in the water two persons of ordinary size.

A very valuable feature of my invention 85 is that the bag when deflated occupies an extremely small space, and therefore does not reduce to any material extent the capacity of the suit case. If the traveler does not wish to be at the trouble of inflating the 90 bag at the commencement of the voyage, there is very little danger in not doing so, as there is in nearly all cases quite sufficient time to remove the clothes from the suit case and inflate the bag at the last minute. 95

A device of this kind, which will sustain a person in the water for many hours, or even days if necessary, is of great value now that nearly all the ships are equipped with wireless apparatus by which persons at a 100 distance would be at once informed of the shipwreck and its locality, so that a survivor does not have to keep afloat long before he is rescued.

I claim:—

105 In combination with a traveling case of comparatively strong material having a slot opening in an edge thereof, a rubber bag

contained therein and having a filling tube extending through said slot and a pneumatic tire valve in said tube, and a loose sheet of protective material in said case secured to one side thereof independently of the bag and extending over the bag.

5 In testimony whereof I have hereunto set

my hand in the presence of two subscribing witnesses.

BALTHASAR ZOPFI.
